BACK REST FOR FURNITURE

Robert H. Monroe, East Orange, N. J., and Marvin K. Culbreth, Wilton, Conn., assignors to Molla Incorporated, Westbury, N. Y., a corporation of New York

Application November 21, 1957, Serial No. 48,597

Term of patent 14 years

(Cl. D15—11)

Fig. 1 is a front elevational view of a back rest for furniture showing our new design.

Fig. 2 is a top plan view thereof; and

Fig. 3 is a section on the line 3—3 of Fig. 1, omitting the background showing.

We claim:

The ornamental design for back rest for furniture, as shown.
